Primary Examiner — Ricky Pham(57) **CLAIM**

The ornamental design for a lid for a beverage container, as shown and described.

DESCRIPTION

FIG. 1 is a front, top perspective view of a lid for a beverage container showing our new design;

FIG. 2 is a rear, bottom perspective view thereof;

FIG. 3 is a front view thereof;

FIG. 4 is a rear view thereof;

FIG. 5 is a left view thereof;

FIG. 6 is a right view thereof; and,

FIG. 7 is a top view thereof.

No claim is made to the bottom view, which is omitted from the drawings.

The dash-dash broken lines throughout the drawing figures depict portions of the lid for a beverage container that form no part of the claimed design. The broken lines and unshaded surfaces bounded by broken lines form no part of the claimed design.
